ULTRA HIGH FREQUENCY ANTENNA SYSTEM

George H. Brown and Robert F. Lewis, Haddonfield, N. J., assignors to Radio Corporation of America, a corporation of Delaware

Application June 30, 1939, Serial No. 282,284

5 Claims. (Cl. 250—11)

This invention relates to an ultra high frequency antenna system and has for its principal object the provision of an improved antenna system which combines structural rigidity with a substantially uniform radiation pattern, and which is adapted to be installed on high buildings, or the like, to provide a maximum range of transmission.

The use of a plurality of antennas to provide increased radiation, or to control the radiation pattern, has been suggested previously. In order to obtain the maximum range of radiation at ultra high frequencies it is desirable to mount the antennas well above surrounding objects. At the same time, however, it is necessary to provide a system in which the effect of the supporting structure on the radiation pattern, if not neutralized, is taken into consideration in providing the desired radiation characteristic. It is therefore a further object of this invention to provide a horizontally or vertically polarized antenna system comprising a plurality of dipole antennas in which the metallic surface of the supporting structure not only shields the antennas from each other but directs the radiation outwardly so as to provide the desired radiation characteristic. A further object of this invention is to provide an improved dipole antenna structure which has sufficient physical rigidity to withstand high wind velocities, and which is further provided with means for preventing accumulations of ice and sleet which would be dangerous not only to the antenna structure itself but to persons and objects below if a sufficiently large formation should occur and become dislodged from the antenna.

This invention will be better understood from the following description when considered in connection with the accompanying drawings in which Figure 1 is a schematic drawing, partly in cross section, illustrating the general arrangement of an antenna system built in accordance with this invention; Figure 2 is a plan view and Figure 3 is an elevation illustrating an antenna arrangement in accordance with this invention; Figure 4 is a view showing the constructional details of a dipole antenna; and Figure 5 is a sectional view of a transmission line utilized in connection with the antenna illustrated in Figure 4; and Figure 6 is a view of a section of one antenna transmission line illustrating the inductive and capacitive correcting sections.

In accordance with our invention a plurality of dipole antennas are mounted in a horizontal or vertical plane parallel to and substantially a

quarter wave length from the respective faces of a supporting structure, which may be the tower of a high building, or the like. In order to increase the radiation in the direction of the horizon we have found that a second similar antenna system may be utilized. The second system is located approximately a half wave length below the first, and consists of identical dipole antennas similarly connected.

10 Referring to Fig. 1, a system comprising upper and lower groups of horizontal dipole antennas is graphically illustrated. The upper group comprises four dipole antennas 7, 9, 11 and 13 which are preferably mounted opposite the four faces of the supporting structure, as is indicated by the "north," "east," "south" and "west" designations. The lower group comprises four similar dipole antennas 15, 17, 19 and 21 which are parallel to the respective antennas of the upper group.

15 The various antennas are energized by a transmitter 23 which is connected to the various antennas through an appropriate transmission line network which consists of concentric line conductors by means of which each arm or element of each dipole antenna is coupled to the transmitter. In order to avoid confusion, in Figure 1 a single line has been used to indicate each concentric transmission line. The terminal ends of 20 the lines, however, have been drawn in greater detail to illustrate the inner and outer conductors. Rectangles 30 indicate impedance correcting sections which are connected to each transmission line, and which are illustrated in greater detail in Figs. 4 and 6.

25 Parallel connections are made between transmission lines which are connected to corresponding elements. By the term "corresponding elements" as herein used in the specification and claims is meant the elements of each dipole antenna which extend in the same direction from the center of the dipole when viewed facing each antenna from within the supporting structure. Thus, all horizontal dipole elements which point 30 in a clockwise direction are "corresponding elements," as are those pointing counterclockwise. In the case of vertical dipoles all upwardly extending elements are "corresponding elements" as are all downwardly extending elements. Suitable coupling transformers are utilized to provide an impedance match between the parallel lines and the transmitter output impedance. Thus, element 25 of the upper north dipole 7 is connected to the corresponding element 29 of the upper east dipole 9 by a concentric line 33, while

the other corresponding elements 27 and 31 respectively are also connected together by a transmission line 35. Transmission lines 33 and 35 are connected, respectively, to coupling transformers 37 and 39 by means of transmission lines 34 and 36. The upper south and upper west dipole antennas have corresponding elements connected in parallel in like manner and are also connected to coupling transformers 37 and 39 by means of two transmission lines 41 and 43 respectively. The antennas of the lower group are connected in a similar manner, corresponding elements 49, 51 of the lower north and east antennas being connected to coupling transformer 39 by a transmission line 45, while the remaining elements 53, 55 are connected to coupling transformer 37 through a transmission line 47. The south and west antennas of the lower group are connected in like manner to the coupling transformers by a pair of transmission lines 57 and 59.

The coupling transformers are of identical construction. Transformer 37, for example, consists of a closed metallic drum 61 of large diameter, a central cylindrical conductor 63 of less diameter which is connected to one end of drum 61, and an inner conductor 65, all concentrically arranged. The axial length of the central cylindrical conductor 63 is approximately a quarter wave length, so that a high impedance is established between the open end of the central conductor and the drum. The ratio of the inner diameter of the drum 61 to the outer diameter of conductor 63 is preferably as large as possible, so that the impedance at the resonant frequency is likewise large, and the change of impedance for frequencies on either side of resonance is minimized. The ratio of the inner diameter of the central conductor 63 to the outer diameter of conductor 65 is selected to provide a proper impedance to match the impedance of the antenna transmission lines. We have found this value to be of the order of 72 ohms.

The connection of the transmission lines within the coupling transformers is made so that a proper phase relation in the various antenna elements is established. The arrowheads on the antenna elements and transmission lines indicate the instantaneous current flow in the system. Thus, transmission lines 59 and 47 are connected in parallel within the coupling transformer 37, and are connected to the inner conductor 65. Transmission lines 41 and 34 are connected in parallel within coupling transformer 37, and are also connected to the open end of the central conductor 63. The currents in the first two transmission lines are, therefore, of a given phase, while the currents in the last-named transmission lines are in phase opposition thereto. Coupling transformer 39 is similarly connected to the transmission lines. Thus, transmission lines 36 and 43 are connected to the open end of the central conductor 67, while transmission lines 57 and 45 are connected to the inner conductor 69.

A third coupling transformer 71 is provided to connect the transmitter 23 to the two coupling transformers 37 and 39, and to provide a suitable impedance match. Transformer 71 is similar to the other transformers and is provided with two output transmission lines 73 and 75 which are connected respectively to the coupling transformers 37 and 39. It will be noted that the currents feeding the two last-named coupling transformers are in phase opposition, and consequently that the currents in the output trans-

mission lines which are connected to the respective inner conductors 65 and 69 are likewise in phase opposition.

The physical arrangement of the antennas on a supporting structure is best illustrated by reference to Figures 2 and 3. The dipole antennas 7, 9, etc., are arranged parallel to the four faces of a building 77 and are placed so as to produce horizontally polarized radiations, although, if desired, the dipole antennas may be positioned vertically to produce vertically polarized radiations. The radiating elements of the antennas are spaced approximately a quarter wave length from the adjacent face of the building. By providing a metallic facing on the four sides of the building, the radiating energy from one antenna is effectively prevented from reaching the other antennas and is reflected outwardly from the building surface. The resultant radiation pattern is substantially uniform, although there is a tendency for the pattern to assume a somewhat rectangular shape.

The actual physical construction of one of the dipole antennas is illustrated in Figs. 4 and 5. A unique arrangement is illustrated in which the radiating elements 79 and 81 are rigidly supported by the two tubular outer conductors 83 and 85 of the transmission lines. The outer conductors 83 and 85 terminate at their outer end at an end plate 87, which is provided with two openings through which the inner conductors 89 and 91 are passed. A suitable cap 93 is securely fastened to the end plate 87. Radiating elements 79 and 81 are mounted by means of suitable insulators 95 and 97 on opposite faces of the cap 93. Connections are made within the cap between the radiating elements and the inner conductors of the transmission lines. This may be accomplished by means of junction blocks 99 and 101, which are suitably drilled, or are provided with clamps to receive the respective conducting elements.

Conductors 83 and 85 are brought through the building wall 113 and securely fastened thereto in any suitable fashion. Within the building and approximately a quarter wave length from the wall two correcting networks 115 and 117 are connected to the two lines. Each network comprises an inductive and a capacitive correcting section, the construction and operation of which will be described hereinafter.

To avoid ice formations on the antenna structure, provision has been made for applying heat to the entire structure. Small hollow tubes 103 and 105 are mounted on and are parallel to tubes 83 and 85, and heating elements 104, 106 are placed within the small tubes. The heating elements are likewise extended within the two radiating elements 79 and 81 which are made hollow to receive the heating elements. Suitable insulating bushings are provided where necessary to prevent the heating elements from short-circuiting to the hollow tubes 103, 105, or the antenna elements 79, 81. However, the heating elements are electrically connected to the outer ends of the radiating elements, at points 107, 109, so that the antenna itself provides the return path for the heating currents. The heating elements are connected to any suitable source of heating current, such as a generator 111. In order to provide the maximum heating efficiency, the hollow tubes 103, 105 containing the heating elements are preferably mounted beneath the transmission line conductors. A shorting bar 86 is slidably mounted on the hollow tubes 103, 105.

The position of this bar is adjusted to tune the outer portion of the tubes to quarter wave resonance. The heating tubes are clamped to the transmission line conductors at this point, which is a voltage minimum, by a pair of clamps 90, 92.

We have found that the metallic cap 93 adds a certain amount of lumped capacitance to the transmission line and antenna elements, largely due to the capacity of junction blocks 99 and 101. In order to provide compensation and to adjust the electrical resonant characteristics of the antenna, the inner conductors 89 and 91 of the transmission line which is used to support the antenna may be made in sections of different diameters, as illustrated in Fig. 5. The first quarter wave section, for example, has a diameter which provides an impedance match to the antenna impedance. The next quarter wave section 89a of the inner conductor has a diameter somewhat less than the diameter of the preceding section. In addition, the length of this section is slightly less than a quarter wave so as to provide an inductive reactance which compensates for the excessive capacitive reactance of the antenna itself.

If the antenna arrangement illustrated is to be used for the transmission or reception of speech its impedance will be sufficiently uniform through the range of side-band frequencies. However, where television video signals are to be transmitted it is advisable to provide a correcting network which has an impedance versus frequency characteristic suitable to provide compensation over the extremely wide range of side-band frequencies which are utilized. To illustrate a preferred embodiment of such a correcting network reference is now made to Figs. 4 and 6.

To each transmission line two correcting sections are connected. One of the correcting sections 115, is inductive and the other, 119, is capacitive and the two are adjusted to parallel resonance at the operating frequency. The sections comprise inner, 121, and 123, and outer, 125 and 127, concentric conductors which are respectively connected to the inner and outer conductors of the antenna transmission line, as shown in Fig. 6.

A shorting plug 129, which is slidably mounted within each inductive section, is arranged to short circuit the inner and outer conductors. The inner conductor of each capacitive section terminates in a plate 131 which is in capacitive relation to an adjustable plug 133. By adjusting the positions of the plugs the correcting sections of each transmission line may be tuned to parallel resonance, and may be given any desired inductance-capacity ratio. This ratio determines the slope of the impedance versus frequency characteristic so that the characteristic of the line, looking toward the antenna, may be compensated by a reciprocal characteristic of the shunt-connected correcting sections.

While Fig. 1 represents the preferred arrangements, it is possible to eliminate the upper or lower group of dipole antennas and utilize one antenna opposite each face of the building. Since, as we have pointed out above, the addition of the lower group of antennas increases radiation in the direction of the horizon, the arrangement illustrated is preferred, although the system may be simplified by the suggested modification. If such a modification is made, one of the coupling transformers 37 and 39 may be eliminated, as well as the coupling transformer 75

71. In such a case, the transmission lines from the antennas will be connected to the same coupling transformer, it being necessary only to ascertain that the proper phase relationships are maintained.

We have thus described an antenna system which is suitable for use at ultra high frequencies and which provides substantially uniform radiation, and therefore overcomes one of the inherent disadvantages of the dipole antenna, which may be utilized to provide either horizontally or vertically polarized radiation, and which takes advantage of the reflecting surface provided by a supporting structure such as a building, or the like.

We claim as our invention:

1. An ultra high frequency antenna system comprising a supporting structure having a plurality of angularly disposed faces, a plurality of dipole antennas each having coaxially extending radiating elements, at least one of said antennas being adjacent and substantially parallel to each face of said supporting structure, and means for producing in phase currents in corresponding elements of said dipole antennas, said structure faces being adapted to reflect energy radiated from said elements and being of sufficient area to shield the antenna adjacent one face from antennas adjacent the other faces so that a substantially uniform radiation pattern in a horizontal plane is thereby produced.

2. An ultra high frequency antenna system comprising a supporting structure having a plurality of angularly disposed faces, a plurality of horizontal dipole antennas each having coaxially extending radiating elements, at least one of said antennas being adjacent and substantially parallel to each face of said supporting structure, and means for producing in phase currents in corresponding elements of said dipole antennas, said structure faces being adapted to reflect energy radiated from said elements and being of sufficient area to shield the antenna adjacent one face from antennas adjacent the other faces so that a substantially uniform radiation pattern in a horizontal plane is thereby produced.

3. An ultra high frequency antenna system comprising a supporting structure having four angularly disposed faces, four dipole antennas each having coaxially extending radiating elements, one of said antennas being adjacent and substantially parallel to each face of said supporting structure, and means for producing in phase currents in corresponding elements of said dipole antennas, said structure faces being adapted to reflect energy radiated from said elements and being of sufficient area to shield the antenna adjacent one face from antennas adjacent the other faces so that a substantially uniform radiation pattern in a horizontal plane is thereby produced.

4. An ultra high frequency antenna system comprising a supporting structure having a plurality of angularly disposed faces, a plurality of dipole antennas each having coaxially extending radiating elements, at least one of said antennas being mounted a quarter wavelength from and substantially parallel to each face of said supporting structure, and means for producing in phase currents in corresponding elements of said dipole antennas, said structure faces being adapted to reflect energy radiated from said elements and being of sufficient area to shield the antenna adjacent one face from antennas adjacent the

other faces so that a substantially uniform radiation pattern in a horizontal plane is thereby produced.

5. An ultra high frequency antenna system comprising a supporting structure having a plurality of angularly disposed vertical faces, a plurality of horizontal dipole antennas each having coaxially extending radiating elements, at least one of said antennas being adjacent and substantially parallel to each face of said supporting structure, and means for producing in

5 phase currents in corresponding elements of said dipole antennas, said structure faces being adapted to reflect energy radiated from said elements and being of sufficient area to shield the antenna adjacent one face from antennas adjacent the other faces so that a substantially uniform radiation pattern in a horizontal plane is thereby produced.
